UNITED STATES PATENT OFFICE.

PETTIS A. REID, WALTER V. REID, AND JAMES KELLEY, OF RICHMOND, INDIANA;
SAID WALTER V. REID AND SAID JAMES KELLEY ASSIGNORS TO SAID PETTIS
A. REID.

WIRE-FABRIC MACHINE.

1,344,595.

Specification of Letters Patent. Patented June 22, 1920.

Application filed February 15, 1910. Serial No. 543,990.

To all whom it may concern:

Be it known that we, PETTIS A. REID, WALTER V. REID, and JAMES KELLEY, citizens of the United States, residing at Richmond, in the county of Wayne and State of Indiana, have invented certain new and useful Improvements in Wire-Fabric Machines, of which the following is a specification.

10 In our application Serial No. 262,966, filed May 29, 1905, (which became Patent No. 1,160,089, granted Nov. 9, 1915) we show a series of loopers and twisters operating in sequence on account of the progressive loop drawing involved in the operation of that machine.

15 In this application we show and claim two such series for making two widths of fencing simultaneously, and on account of the sequential operation the two series are arranged to draw in surplus material for the loops from opposite ends of the stay-wire.

20 In making a single width of fencing, it is preferable for the sake of uniformity of appearance to have all the twisters rotating in the same direction, and hence the whole series work sequentially from one marginal twister toward the other marginal twister, so as to have the coils alike across the width of fencing. But when making a double width of fencing (for division into separate widths) the arrangement shown and described herein may be utilized without disadvantage, since the appearance of the coils of each width will be similar. Also, if symmetry and uniformity of appearance may be sacrificed for speed, the same arrangement may be utilized in making a single width of fencing.

25 Referring to the accompanying drawings, which form a part of this specification:

Figure 1 is a diagrammatic face view of a double series of loopers and twisters such as disclosed in our said application Serial No. 262,966, the respective groups or series working sequentially and both during the same time;

30 Fig. 2 is a diagrammatic plan view of a fence-making mechanism according to Fig. 1;

Fig. 3 is a face view of the four middle loopers and twisters of the double series of Fig. 1, shown beginning action at the center of the stay wire; and

55

Fig. 4 is a cross-section of Fig. 2, showing only the principal parts associated with one looper and twister.

Except for the arrangement of loopers and twisters in two series operating in the manner stated, the mechanism illustrated in the drawings is the same as shown and described in our said application Serial Number 262,966, to which reference may therefore be made for a detailed description, and in this specification a brief indication of the principal elements will suffice.

The individual loopers and twisters of the respective series of the whole complement or so-called double series are indicated by the consecutive numbers 1, 2, 3, 4, etc., indicating the sequence of operation of each series, and also indicating the corresponding twisters of the two series which work in pairs since both series are in operation at the same time.

20 *a* denotes the twister-spindles; *b* the twister-heads; *c* bevel pinions on the spindles; and *d* the drive-wheels having segmental gears for engaging said pinions and also having cams for operating levers *e* which control slip-collars *f* which in turn control the retractable looping pins *g* in the twister-heads.

25 *h* denotes the feed-rolls for the stay-wire; *i* the separable guide-tubes which conduct the stay wire across the series of strands that are threaded through the spindles; *j* the lifters or positors for displacing the stay wire from the guides; and *k* the beaters or presser-feet which, when the stay wire is brought within their reach, move it to within the operation of the tools of the twister-heads and hold it there. These beaters or presser-feet are formed to straddle the strands, as explained in our said application Serial No. 262,966, and thus also serve as line wire guides.

30 *m* denotes a stay wire cutter beside the marginal twister (No. 4) at the feed-roll side of the series. This cutter may sever the stay either just before or just after the

- operation of said marginal twister. In the former case the marginal twister would be a simple end twister as shown; in the latter case it would be a looper and twister.
- 5   n is a middle cutter which may or may not be used to sever the stay wire in two either before or after the operation of the twisters. If used before, the two middle or innermost twisters (No. 1) would be merely 10 end twisters each rotatable in a reverse direction to the succeeding twisters of the same series. If used after, or if not used at all, the said middle twisters would be loopers and twisters as shown.
- 15   The feed-rolls h feed a surplus of the stay wire beyond the marginal twister farthest from the feed-rolls, and in operation the looping tools of the one series of twisters take up the material for the loops from 20 such surplus, while the looping tools of the other series of twisters draw in the necessary material through the feed-rolls h, which allow the stay wire to slip therethrough as stated in our said application 25 Serial No. 262,966.
- 20   A gripper o may be used beyond the marginal twister farthest from the feed-rolls, for tensioning the stay wire against the resistance of the looping tools, especially if 30 the knife n be operated preliminary to the stay-applying operation. But the use of such gripper is not indispensable, since the stay wire may be sufficiently held by the presser-feet k.
- 35   If instead of the feed-rolls h, a pre-severed stay length should be fed to the twisters, as in our former Patent No. 721,605, dated Feb. 24, 1903, the wire being 40 straight however, in such case the stay length so severed would of course have the necessary surplus at both ends, and the use of grippers o at both sides of the machine would be preferable; as in the Kelley & Reid stay-machine Patents Nos. 721,567 and 45 721,568, where a stay length was furnished with the required surplus at both ends and grippers for tensioning were employed at both sides.

50   It will be noticed that the two series of drivers d are identical except for their opposite disposition, and the drivers of each series are set at successively different angles for operating the twisters in sequence in the same manner as in our said application 55 Serial No. 262,966.

We claim:

1. A wire fence machine, including two sets or series of wire-connecting devices, the devices of the two sets or series arranged in 60 line with one another, means for feeding a stay-wire adapted to be operated on by all of said devices, means for severing a stay-length from said stay-wire, and a cutter for

severing the stay-length into two stay-sections.

65

2. A wire fence machine, including two sets or series of wire-connecting devices for manufacturing two widths or rolls of fence simultaneously, a single means for projecting a stay-wire across said two sets of devices, means for severing a stay-length from said stay-wire, means for operating certain of the two sets of devices in pairs, and during such operation draw in surplus wire from opposite ends of said sets of devices, 70 and means for severing the stay-length in two, to produce separable stay-sections for each roll of fence.

75

3. A wire fence machine, including two sets or series of wire-connecting devices for manufacturing two widths or rolls of fence simultaneously, means for feeding a stay-wire across said sets of devices, means for severing a stay-length from said stay-wire, means for successively bringing the devices 80 of each set into operation and for operating corresponding devices of each set in pairs, and means operating after the first pair of 85 corresponding devices of the two sets of devices begins to operate, for severing the stay-length into two stay-sections, to produce separable stay-sections for each roll of fence.

90

4. A wire fence machine, including two sets of wire-connecting devices, the same 95 being arranged to produce two corresponding rolls or widths of fence simultaneously, or two rolls or widths of fence of varying widths, means for feeding a single stay-wire to said two sets of devices, means for severing a stay-length from said stay-wire, means for operating certain of the devices of said 100 sets of devices in pairs to connect portions of said stay-length to wires of separate rolls and for bringing said pair of devices into 105 action in succession, each pair coming into action during the operation of another pair, and means operating after the first pair of corresponding devices of the two sets of devices begins to operate, for severing the stay-length in two, to produce separable stay-sections for each roll of fence.

110

5. A wire fence machine, including two sets of wire-connecting devices, the devices of both sets arranged in line with one another, a stay-wire feed adapted to project the stay-wire endwise transversely of said sets of devices, means for severing a stay-length from said stay-wire, means for moving said stay-length laterally and adjacent 115 said devices, means for operating said devices to apply said stay-length to a series, of wires, and a cutter for severing the stay-length intermediate the two sets of devices, for producing separable stay-sections.

120

6. In a wire fence machine, in combina-

125

tion, two sets of aligned coilers, each set adapted to produce a distinct and separable roll of fence simultaneously, a stay-wire feed, means for severing a stay-length from 5. said stay-wire, cutting mechanism disposed between the two sets of coilers for severing said stay-length in two separate stay-sections, and means for operating said cutting mechanism.

In testimony whereof we affix our signatures, in presence of two witnesses.
